CLAIM

The ornamental design for a motorcycle wheel, as shown and described.

DESCRIPTION

FIG. 1 is a front elevational view of a motorcycle wheel showing my new design;

FIG. 2 is a rear elevational view thereof;

FIG. 3 is a left side elevational view thereof, the right side view being a mirror image of FIG. 3;

FIG. 4 is a top plan view thereof;

FIG. 5 is a bottom plan view thereof; and,

FIG. 6 is a perspective view thereof.

The broken lines show portions of the motorcycle wheel that form no part of the claimed design.
